CLAIM

The ornamental design for a stackable tray unit for wall mounting, as shown and described.

DESCRIPTION

FIG. 1 is a front elevational view of a stackable tray unit for wall mounting showing our new design;

FIG. 2 is a rear elevational view;

FIG. 3 is a left side elevational view, the right side being a mirror image thereof;

FIG. 4 is a top plan view;

FIG. 5 is a bottom plan view; and,

FIG. 6 is a perspective view thereof.

*FIG. 1**FIG. 2**FIG. 3**FIG. 4**FIG. 5*FIG. 6
